(57) **CLAIM**

The ornamental design for a liquid container, as shown and described.

DESCRIPTION

FIG. 1 is a front perspective view of a liquid container showing our new design;

FIG. 2 is a front elevation view thereof;

FIG. 3 is a rear elevation view thereof;

FIG. 4 is right side elevation view thereof;

FIG. 5 is a left side elevation view thereof;

FIG. 6 is a top plan view thereof; and,

FIG. 7 is a bottom plan view thereof.

The dash-dot broken lines represent the boundary of the claimed design. The even-spaced dash broken lines are for the purpose of illustrating portions of the article and form no part of the claimed design.

1 Claim, 6 Drawing Sheets(56)
